Ch. Allen

Attorney

UNITED STATES PATENT OFFICE

GEORGE B. ALLEN, OF ATLANTA, GEORGIA

LIQUID-PURIFYING DEVICE

Application filed September 6, 1927. Serial No. 217,793.

This invention relates to a device for purifying liquids, and more particularly beverages such as root beer, gingerale and the like.

An important object of the invention is to provide a porous container in which is arranged a body of a purifying agent such as charcoal or the like and adapted to be submerged in the body of a liquid whereby the latter will be aged, purified and deodorized. A further object is to provide a device of the above mentioned character which may be made of fabric or similar porous material to permit the circulation of the liquid through the body of the purifying agent to permit the latter to take up foreign matter from the liquid whereby the latter will be rapidly aged, purified and deodorized.

A further object is to provide a cloth or similar bag divided to form a compartment for a purifying agent and a compartment adapted to contain crushed stone or the like whereby the specific gravity of the device will be greater than that of the liquid in which it is used so that it will sink in the liquid.

A further object is to provide a cloth or similar bag which is greatly elongated and is adapted to assume a vertical position in a container for liquids whereby the device may be centrally arranged within the liquid to more efficiently permit circulation of the latter through the purifying material.

A further object is to provide a device of the above mentioned character wherein the lower end of the bag contains crushed stone or the like to provide weight means and wherein the greater portion of the upper end of the bag contains a purifying agent of lighter specific gravity than the liquid in which the device is to be used, the specific gravity of the device as a whole being greater than that of the liquid whereby it will sink therein and will remain in an upright position in the liquid.

Other objects and advantages of the invention will be apparent during the course of the following description.

In the drawings I have shown one embodiment of the invention. In this showing,

Figure 1 is a sectional view of a container

showing the device in position therein, parts being shown in elevation, and

Figure 2 is a detail perspective of the device.

The device forming the subject matter of the present invention is adapted to age, purify and deodorize liquids of various characters such as root beer, gingerale and the like, and the liquid may be placed in any suitable container. In the present instance I have illustrated the container as comprising a glass jar 10 having a screw-threaded cap 11 and containing a body of a liquid 12.

The device forming the subject matter of the present invention comprises a bag 13 preferably formed of textile material whereby it will be porous to permit the circulation of the liquid therethrough. The bag is provided centrally thereof with a string 15 or other suitable means adapted to divide the bag into a relatively small lower compartment 16 and a relatively long upper section 17. Weight means 18 is preferably arranged in the lower section of the bag, and such means may comprise crushed stone or the like, for a purpose to be described. The elongated upper section of the bag is provided with a body of a purifying agent 19, such as charcoal or the like, and the upper end of the bag may be tied with a string 20 or the like.

The operation of the device is as follows:

The liquid to be treated is placed in the container and sufficient space is left in the container to accommodate the purifying device. The latter is placed in position in the container as shown in Figure 1. The specific gravity of the purifying agent is materially less than that of the liquid, while the specific gravity of the crushed stone or other weight means is materially greater than the liquid. The proportion of the materials employed is such that the specific gravity of the device as a whole is greater than that of the liquid so that it will sink to the bottom of the container, and it will be obvious that the weighted end of the bag will rest on the bottom of the container, while the latter, as a whole, will assume an upright position. The device preferably is placed centrally of the container as shown in Figure 1 so that all por-

tions of the liquid will be more evenly subjected to the action of the purifying agent. The porous bag permits the material to circulate therethrough to be subjected to the action of the purifying agent, and the latter will age, purify and deodorize the liquid in a much shorter time than can be accomplished by the use of charred kegs or the like. The device has the additional advantage that it may be used in glass, porcelain, and similar containers, and the purifying agent is retained wholly within the bag, thus rendering it unnecessary to filter the liquid. The bag may be left in the liquid for any desired length of time and it will be apparent that the longer the bag remains in the liquid, the greater will be the extent of the desired action.

It is to be understood that the form of my invention herewith shown and described is to be taken as a preferred example of the same, and that various changes in the shape, size, and arrangement of parts may be resorted to without departing from the spirit of the invention or the scope of the subjoined claims.

I claim:

1. A device of the character described comprising an elongated porous fabric container adapted to be arranged in a body of a liquid, liquid purifying means arranged in said container and substantially filling the latter from the top thereof to a point spaced from the bottom thereof, said means possessing a specific gravity less than the specific gravity of the liquid, and material of greater specific gravity than said purifying means arranged in the bottom of said container and substantially filling the latter from the bottom thereof to the lower end of said purifying means, said material providing means for causing said container to maintain a substantially vertical position in said liquid.

2. A device of the character described comprising an elongated porous fabric container adapted to be arranged in a body of a liquid, means for dividing said container into two integral compartments, one compartment being substantially larger than the other, liquid purifying means arranged in the larger of said compartments, said purifying means possessing a specific gravity less than the specific gravity of the liquid, and material arranged in the other of said compartments of greater specific gravity than said purifying means and of greater weight than the weight of said purifying means providing means for causing said container to maintain a substantially vertical position in said liquid.

In testimony whereof I affix my signature.
GEORGE B. ALLEN.
